[57] **CLAIM**

The ornamental design for a set of doorknob notepad dispensers, as shown and described.

DESCRIPTION

FIG. 1 is a front elevation view of a set of doorknob notepad dispensers showing my new design;

FIG. 2 is a side elevation view, the other side being a mirror image thereof;

FIG. 3 is a top plan view, the bottom plan view being a mirror image thereof;

FIG. 4 is an enlarged fragmentary cross-sectional view taken along lines 4-4 of FIG. 1;

FIG. 5 is an enlarged fragmentary cross-sectional view of the perforation between two doorknob tags taken along lines 5-5 of FIG. 1;

FIG. 6 is a perspective view of FIG. 1 thereof; and,

FIG. 7 is a perspective view thereof with one of the dispensers separated along the perforation.

The rear elevation view is a mirror image of the front elevation view. The broken lines showing the outlines of a notepad article on FIGS. 1, 2, 3 and 6 is for illustrative purposes only and forms no part of the claimed design.

The claimed design is fragmentarily shown for convenience of illustration.
